UNITED STATES PATENT OFFICE

147,545

DESIGN FOR A BROOCH OR SIMILAR ARTICLE

George F. Garrison, Providence, R. I.

Application July 30, 1946, Serial No. 132,110

Term of patent 3½ years

(Cl. D45—19)

To all whom it may concern:

Be it known that I, George F. Garrison, a citizen of the United States of America, residing at Providence, in the county of Providence and State of Rhode Island, have invented a new, original, and ornamental Design for Brooch or Similar Article, of which the following is a specification, reference being had to the accompanying drawing, forming part thereof.

I claim:

The ornamental design for a brooch or similar article, substantially as shown.

GEORGE F. GARRISON.
